UNITED STATES PATENT OFFICE

2,493,647

REFRIGERATING STORAGE UNIT

George B. Wagner, Holbrook, Mass., assignor to
Beekman Industries, Inc., New York, N. Y., a
corporation of New York

Application April 30, 1946, Serial No. 660,043

6 Claims. (Cl. 62—91.5)

1

This invention relates to a novel refrigerating apparatus of the nature disclosed in my copending applications Serial Nos. 604,700, now Patent 2,489,510, dated November 29, 1949, and 642,312, filed July 12, 1945 and January 19, 1946 respectively. In those applications I have disclosed a storage chamber refrigerated by evaporation gas from Dry Ice conducted from a Dry Ice box through a refrigerant pipe in the chamber, together with means for controlling the temperature in the chamber by controlling the pressure in the pipe.

The invention disclosed in this application relates to a novel refrigerating apparatus of that nature and including a storage chamber refrigerated by the evaporation of Dry Ice from a box associated with the chamber, together with means under control of the temperature in the chamber for automatically controlling the transfer of heat from the chamber to the box in accordance with the temperature in the chamber, it being apparent that such transfer of heat causes increased evaporation of the Dry Ice and a consequent lowering of the temperature in the chamber.

In its preferred form, the invention embodies a refrigerating unit for shipping perishable products and comprises a box-like container having a storage chamber within insulated walls and open only at its top end, a removable cover closing this end of the chamber, and means including an insulated Dry Ice box supported by the cover in the chamber and thermostatically operated means for automatically maintaining a predetermined temperature in the chamber. The production of such an improved unit in which the refrigerating mechanism is carried by the cover, leaving the storage chamber free for receiving and removing perishable products when the cover is removed, comprises the primary object of the invention.

These and other features of the invention will be best understood and appreciated from the following description of a preferred embodiment thereof selected for purposes of illustration and shown in the accompanying drawings in which—

Fig. 1 is a side elevation, partly in vertical section, of an apparatus embodying my invention,

Fig. 2 is an enlarged side elevation of a portion of the apparatus,

Fig. 3 is a bottom plan view of Fig. 2, and

Fig. 4 is a further enlarged side elevation of the device, partially in vertical section on line 4—4 of Fig. 2.

In the drawings, 10 indicates a double walled

2

container having a sheet aluminum lining 12, a strong and light-weight fibre outer wall 14 and thick light-weight insulation 15 therebetween, a reinforcing rib 16 of wood being provided at the top. Lifting handles 18 are secured to opposite sides of the container and the interior provides a storage chamber 20. The top end of the container is open and adapted to receive a cover 22. The cover is double walled and fully insulated and is provided with a rubber seat 23 for contacting the top end of the container. Straps 24 are employed to hold the cover tightly in place on the container.

Refrigerating apparatus including a sheet aluminum box 26 is supported by U-shaped brackets 28 on the bottom wall of the cover. Disposed within the box 26 is a sheet aluminum Dry Ice containing box 30 fully insulated from the box 26 by thick insulation 32. One end of the box 30 is open to permit charging with Dry Ice 34 and a closure with insulation 36 is provided for closing this end of the box.

A tapered opening 38 is formed through the insulation housing 32 to the box 30 at the bottom of the unit and a gate 40 containing thick insulation 41 is provided in this opening. The position of this gate in the opening is automatically controlled by thermostatically operated means in the storage chamber. The thermoelectric means illustrated comprises an expandable metal bellows 42 welded at its top end to the bottom wall of the cover and having its bottom end welded at 44 to a bar 46. The ends of the bar carry two rods 48 extending downwardly through tubes 50 disposed through the housing 26. The gate 40 is carried on a bar 52 supported on the bottom ends of these rods. The bellows is filled with ethyl chloride or other temperature sensitive fluid.

The Dry Ice box is preferably vented through a refrigerating coil 54 extending outwardly therefrom through the box 26, and from thence through the storage chamber and outwardly through the cover at 56. Venting pressure is controlled by an adjustable valve 58 as in my said copending applications.

A temperature of -110° F. is normally maintained in the Dry Ice box 30 and the temperature to be maintained in the storage chamber 20 depends on the product contained. I have employed this apparatus in the storage of perishable products and have maintained a predetermined temperature of 45° F. in the storage chamber uniformly within less than 2° over a period of 104 hours. It will be apparent that transfer

of heat from the storage chamber 20 to the box 30 will increase evaporation of the Dry Ice and thereby lower the temperature in the storage chamber and my invention contemplates the controlling of the temperature in the storage chamber by a variable transfer of heat from the chamber to the box under automatic control of the temperature in the storage chamber.

The edge walls of the gate 40 and the cooperating walls of the housing 26 diverge outwardly and the gate 40 is so constructed and mounted that these walls closely approach but do not come into tight contact when the gate is closed, thereby preventing any freezing of the gate in its closed position. As one means for performing this function, I have illustrated stops 53 at the ends of the bar 52, the stops being adapted to engage the housing 26. The temperature maintained within the storage chamber can be varied by adjusting the gate supporting balance provided by the bellows 42. In the drawings I have illustrated two tension springs 60 hung on bolts 62 carried by the cover 22 and connected at their bottom ends to the rods 48. The tension springs can be varied by rotating thumb nuts 64 in threaded engagement with the bolts and such action adjusts the position of the gate 40 relative to and in the direction of the opening 38. It will be apparent that such adjustment permits more or less heat to pass through the opening from the chamber 20 and serves to vary the controlled temperature of the chamber. It will be understood that various products contained within and shipped in the container require the maintenance of different temperatures and this adjustment permits the maintaining of the temperature required of the particular product.

Having thus disclosed my invention what I claim as new and desire to secure by Letters Patent is:

1. A refrigerating storage unit comprising a box-like container embodying insulated walls enclosing a storage chamber having an opening at one end through said walls, a removable cover for closing said one end of the chamber, a closed Dry Ice box in the chamber, an insulation housing enclosing the box except for an opening through the housing from the chamber to the box, means supporting the box and housing on the cover, a closure gate in the last named opening, and a thermostatically operated bellows supported on the cover and connected to and

adapted to hold the gate in closed position when the temperature in the chamber is below a predetermined degree and to open the gate when the temperature exceeds said degree.

5 2. The refrigerating unit defined in claim 1 in which the edge walls of the gate and the cooperating walls of the housing diverge outwardly, and means supporting the gate for straight line movement outwardly and inwardly of the opening by said thermostatically operated bellows.

10 3. The refrigerating unit defined in claim 1 plus means for preventing complete contact closure of the gate in the opening.

15 4. The refrigerating unit defined in claim 1 plus means cooperating with the thermostatically operated bellows and gate for adjustably varying the position of the gate in the opening in the path of its movement under the action of the bellows.

20 5. The refrigerating unit defined in claim 1 plus resilient means operating on the gate to move it toward said closed position, and means for varying the effective action of the resilient means on the gate.

25 6. A refrigerating storage unit comprising a box-like container embodying insulated walls enclosing a storage chamber having an opening at one end through said walls, a removable cover for closing said end of the chamber, a closed Dry Ice box extending downwardly from the cover into the chamber, an insulation housing enclosing the box except for an opening through the bottom wall of the housing from the chamber to the box, means supporting the box and housing on the cover, a closure gate in the last named opening, and means including rods extending through the housing and thermostatically operated means in the chamber for supporting the gate and automatically moving it in the closing-opening directions in accordance with temperature changes in the chamber.

40 GEORGE B. WAGNER.
